UNITED STATES PATENT OFFICE.

FRANK CLAYTON HERBERT, OF HAMPSTEAD, LONDON, ENGLAND.

DEVICE FOR PREVENTING THE FRAUDULENT REFILLING OF BOTTLES.

1,140,744.

Specification of Letters Patent. Patented May 25, 1915.

Application filed September 27, 1913. Serial No. 792,123.

To all whom it may concern:

Be it known that I, FRANK CLAYTON HERBERT, a citizen of the United Kingdom of Great Britain and Ireland, and resident of 5 22 Roderick road, Mansfield Road, Hampstead, London, England, have invented certain new and useful Improvements in Devices for Preventing the Fraudulent Refilling of Bottles, of which the following is a 10 specification, such as will enable others skilled in the art to which it appertains to make and use the same.

This invention relates to a stopper-like device for preventing the fraudulent refilling 15 of bottles and refers to that type of device which can be applied to a bottle and removed therefrom as a unit so as to be capable of repeated use with different bottles and without the necessity of breaking the bottles to 20 remove the device and also without special preparation of the neck of the bottle.

My improved device is made of non-metallic substances such as "porcelain" and in that manner in which the parts are assembled 25 together in raw state and the casing or outside parts are fixed to each other by firing while the valve inside is left free.

A gravity valve is employed and is preferably of partial ball shape and of such size 30 and weight that it will return to its seat when the bottle is turned from an inverted position before the bottle reaches the horizontal position, and no controlling weight is required to push or hold the ball on its 35 seating.

The device is attached to the bottle neck by partial insertion therein and by suitable means such as an external metal sleeve of substantially known or suitable kind.

40 It will be seen from the above descriptions that the device will be very easily fixed in the neck of the bottle, it being necessary only to thrust it in as one would a stopper and secure it and thus the invention is applicable to practically any ordinary bottle 45 having a neck sufficiently large to receive the device which will enable an ordinary bottle to be made into a "non-refillable" bottle by the simple insertion and securing 50 of my device.

One stopper can be used an indefinite number of times and the initial cost is small.

In the accompanying drawings three views 55 of that form of my invention which is designed to be placed upon the neck of an ordinary spirit bottle are shown, Figure 1 being

a vertical section on line C—D of Fig. 2, and Fig. 2 a cross section on line A—B of Fig. 1. Fig. 3 is an external view of the device.

For the purpose of showing the invention 60 clearly and to differentiate same by reference letters I have differently section lined the device but it must be understood that the parts referred to as *a*, *b* and *c* are preferably to all intents and purposes integral, being 65 made say of "porcelain" and pressed together to form a unit in manner well known to pottery manufacturers. The "ball" *d* is necessarily not integral with the other part or parts but is contained therein. The external capsule or sleeve *e* is of metal. The cradle or sleeve *a* has a flange *f* adapted to rest upon the top of the bottle neck and to provide also a suitable surface for joining it to the cap or upper part *b*, within which is 75 centrally set a body piece *c* connected by radial arms to the part *b*.

The sleeve *a* has a central aperture the sides *g* of which form the seat for the "ball" *d* and inside the sleeve lugs *h* are arranged 80 and act as guides for the ball *d* and form passages *i* for the outflow of liquid. The innermost end of the sleeve or cradle *a* is annular and presents a wall *j* to the passages *i* between the lugs *h* the upper surfaces of 85 these walls are shown at a slight downward slope from the center toward the circumference so that a wire or the like inserted from the top and reaching as far as these walls is directed away from the ball which remains 90 upon its seat and prevents the inflow of liquid. A slight projection or pip *k* is left upon the body *c* to prevent the body and the ball sticking together.

What I claim and desire to secure by Letters Patent is:—

1. In a device for preventing the fraudulent refilling of bottles, the combination of a cup-shaped cradle adapted to be seated in the bottle neck and provided on its inner face with spaced vertical ribs and at its bottom with a central opening forming an annular seat comprising a portion of a spherical surface, the outer edge of which is adjacent to the inner face of said ribs; a valve member comprising a portion of a sphere slightly greater than a hemisphere and adapted to seat snugly in said annular seat; and a cap joining the upper part of the cradle and provided with a central opening in its top and having in its lower part a cylindrical body held spaced from the walls 105 110

and top of the cap and having its lower part projecting into said cradle to a level a slight distance above said ribs and valve member, and provided with a small central projection.

2. In a device for preventing the fraudulent refilling of bottles, the combination of, a bottle neck, a cup shaped cradle resting on top of the bottle neck and projecting downwardly therein, and provided at the bottom with an annular seat forming a portion of a spherical surface; a valve member comprising a portion of a sphere greater than a

hemisphere and resting in said seat; and a cap resting on the upper part of said cradle and having therein a body piece spaced and supported from the walls thereof by means of radial arms and having its lower face disposed above said valve member.

In witness whereof I have hereunto set my hand in presence of two witnesses.

FRANK CLAYTON HERBERT.
